UNITED STATES PATENT OFFICE.

FRANKLIN ALFRED ERRINGTON, OF NEW YORK, N. Y.

COLLAPSIBLE TAP.

SPECIFICATION forming part of Letters Patent No. 784,208, dated March 7, 1905.

Application filed August 21, 1900. Serial No. 27,553.

To all whom it may concern:

Be it known that I, FRANKLIN ALFRED ERRINGTON, a citizen of the United States of America, residing in New York city, borough 5 of Richmond, State of New York, (post-office Stapleton, New York,) have invented certain new and useful Improvements in Collapsible Taps, of which the following is a specification.

My invention relates more particularly to 10 taps in which the chasers or jaws move longitudinally of the supporting-body to open to and close from the cutting position; and the principal object of my invention is to provide a simple means of adjusting the cutting 15 diameter of the jaws and of retaining the chasers in coöperative position relatively to the body; and my invention further consists in the novel details of improvement that will be more fully hereinafter set forth and then 20 pointed out in the claims.

Reference is to be had to the accompanying drawings, forming a part hereof, wherein—

Figure 1 represents a plan view of the cutting end of a device embodying my invention, 25 the jaws being shown in the cutting position. Fig. 2 is a vertical cross-section on the line 2 2 of Fig. 1, the jaws being shown in the collapsed position; and Fig. 3 is a similar view 30 except that the chasers are shown in the cutting position. Fig. 4 is a cross-section of Fig. 3 on the line 4 4, showing a method of camming the external thrust-faces of the device to render them adjustable; and Fig. 5 is a 35 plan view of the rear or driving end of the device, showing a method of holding the center piece from movement independently of the body.

Similar numerals and letters of reference 40 indicate corresponding parts in the several views.

A body 1 is shown adapted at its rear or inner end 1^a for connection with suitable driving means, and at the other or outer end 1^b with a longitudinal slot or slots 1^c, adapted to 45 receive a chaser or chasers 2. The body 1 is provided with an axial bore *x* and radial bores *y* *z*, the radial bores being shown screw-threaded to mesh with set-screws 1^d. A center piece 3 is shown located in axial bore *x* and

held in any one of a series of desired positions 50 relatively to body 1 by the set-screws 1^d engaging an adjusting-nut *G*, the latter meshing with a screw-threaded projection 3^a of center piece 3 and held in any desired position therealong by any usual nut-lock arrangement, such as the jam-nut *H*. The nut *G* is flattened on the sides to bear squarely upon the flat ends of the set-screws 1^d. This arrangement holds the center piece 3 from independent movement in any direction relatively 60 to body 1. The center piece 3 is provided with a longitudinal succession of projections *E* and indentures *F*. The outer surfaces 3^c of the projections *E* are shown cammed laterally of the center piece 3 to provide adjustable external thrust-faces 3^e thereupon. (See Fig. 4.) The chaser or chasers 2 are inserted in slot or slots 1^c, the inner end of each chaser abutting against its respective slot-stop face 1^e when in the cutting position, each chaser being thus 70 connected to rotate in unison with body 1 and left radially and longitudinally movable relatively to body 1. The outer end surface of each chaser is provided with serrations 2^a, extending transversely of the chaser at an 75 oblique angle to the axis of the body 1 or screw-cutting teeth of any desired pitch. I have shown the inner end portion of the chaser having a transverse groove *o* to receive a retaining and alining spring 4, whose ends are 80 joined together in such a manner as to enable said spring to surround the chasers 2 and body 1 and exert a yielding pressure against the movement of chasers 2 outwardly radially 85 of the body 1. To protect spring 4, I preferably surround it by guards 4^a at each intersection with the chasers 2. The portion of the jaws provided with the spring-groove *o* is preferably shown projecting beyond the periphery 90 of the body sufficiently to enable the spring 4 to clear the periphery of body 1 when the chasers 2 are in the collapsed position, and the groove *o* is preferably deep enough to hold the spring 4 in mesh with the jaws or chasers 2 during the movement of the spring 4 longitudinally of the body with the chasers 2.

The collapsing and expanding of the chasers 2 is effected by providing the inner surface of

each chaser with a longitudinal succession of projections *e* and indentures *f*, corresponding with the projections *E* and indentures *F* of the center piece 3. The inner ends *2^c* of the 5 projections *e* provide internal thrust-faces for the chaser that bear upon the external thrust-faces *3^c* of the center piece 3 during operation, and the indentures *F* of the center piece 3 receive the projections *e* at the same time that 10 the indentures *f* receive the projections *E* of the center piece 3 when the jaws are in the collapsed position. The outer sides *v* of the chaser projections *e* and the inner sides *V* of the body projections *E* are preferably left 15 straight to provide coacting stop-faces to arrest the outward longitudinal movement of the jaws 2, whereas the opposite sides of the projections *e* *E* are preferably sloped at *s* to move the jaws radially of the body 1 when the 20 jaws move longitudinally inwardly of body 1 from the collapsed to the cutting position.

Whenever it is desirable to adjust the cutting diameter of the chasers 2, the set-screws 1^d can be slackened back and the center piece 3 25 either partially or entirely removed from body 1 through bore *x*. The lock-nut *H* is then slackened back, that the adjusting-nut *G* may be turned upon the screw-threaded portion 3^a proportionately to the desired relative angular adjustment of the cam-faces *E* with the radial slots 1^c. Thereupon the lock-nut *H* is tightened up against the adjusting-nut *G*, which again locks the latter in its new position upon center piece 3. When the center piece 35 3 is now placed in operative position in bore *x*, the tightening up of the set-screws 1^d upon the flats of adjusting-nut *G* will cause a partial rotation of center piece 3 relatively to its former position in body 1, thereby securing 40 an angular adjustment of the cam-faces *E* relatively to the slots 1^c, which will bring a new section of the cam-faces *E* under the chasers 2, so that these new external thrust-faces *3^c* (being that portion of the cam-faces *E* upon 45 which the internal thrust-faces *2^c* of the chasers 2 bear when in the cutting position) will now be located at a different position along the outermost surfaces of the cams *E*, and consequently at a greater or lesser distance from 50 the center of body 1, which will make a corresponding variation in the projection of the chasers 2 from the periphery of body 1 when said chasers are in the cutting position. The ability to adjust the cutting diameter of 55 the chasers is a very essential feature, as some adjustment should always be provided to enable the chasers to cut a tight or loose fit, compensate for any variation in hardening, &c.

An abutment or pin 5 prevents the chasers 60 2 from slipping out of the cutting position under the action of gravity when the device is used vertically, as said pin engages the guard 4^a of spring 4 for said purpose. The coacting surfaces of abutment 5 and spring-guard 4^a are adapted to coact together in such

a manner as to form a yielding catch by rounding one of said coacting surfaces sufficiently to permit the spring-guards 4^a to rise over the abutment or abutments 5 when the chasers 2, spring 4, and spring-guards 4^a are moved 70 longitudinally of body 1 by sufficient force to expand the spring 4. The spring-guards 4^a are shown adapted to mesh with the chasers 2 to equalize the movement of the chasers 2, and for this purpose I have preferably shown 75 indentures *O*, provided in the chasers 2 to receive the spring-guards 4^a.

The parts being in the collapsed position shown in Fig. 2, the operation is as follows: The chasers 2 are pushed inwardly of body 1 80 along their respective slots 1^c by pressure suitably applied against their extended outer ends, the spring 4 preserving the alinement of the chasers with the body at all times by pressing the chaser projections *e* against the center 85 piece 3, the sloping faces *s* *S* causing the chasers to move radially outwardly of body 1. When the inner ends of the chasers abut against the stop-faces 1^e of the slots, the chasers will be in their respective operative or cutting positions. This opening of the chasers 2 can be accomplished during the rotation of the device by pressing the outer ends of the chasers against a suitable surface having an aperture that will admit the outer end 1^b of 90 the body. Upon the rotation of either my device or a suitable piece of work having a suitable aperture to be internally threaded or tapped the teeth 2^a of chasers 2 will cut screw-threads into the walls of said aperture upon 95 presentation of the device thereagainst, and the position of the chasers 2 relatively to body 1 will remain constant until the relative movement of the device and the work toward each other is stopped by any suitable means— 100 as, for instance, by using the outer end 1^b of the body as a stop to encounter the bottom surface of the aperture being threaded, whereupon the continued rotation of the rotative member (either body 1 or the work being 105 operated upon) will cause the chasers 2 to continue cutting, while at the same time the oblique serrations 2^a of the chasers 2 will draw the chasers 2 longitudinally of body 1 110 during the cutting operation independently 115 of the external thrust-faces *3^c* by the spiral coaction of the oblique serrations 2^a with the threads already cut in the work until the internal thrust-faces *2^c* of the chasers 2 pass out of line with the external thrust-faces *3^c* of the 120 body 1, whereupon the jaws or chasers 2 will slide inwardly radially of body 1, the projections *e* of the chasers passing within the plane of their respective associate external thrust-faces *3^c* into the indentures *F* of the body 1, 125 and the projections *E* of the body simultaneously entering the indentures *f* of the chasers, and this inward radial movement of the chasers continues during the collapsing operation until the cutting edges of the teeth 2^a 130

clear the threaded walls of the aperture in the work, whereupon the device can be withdrawn from the threaded aperture without stopping or reversing the rotation of the rotative member, (either body 1 or the work being operated upon.)

Having now described my invention, what I claim is—

1. The combination of a body provided with a longitudinal succession of projections and indentures the outer ends of the body projections providing external thrust-faces, a chaser or chasers connected with the body to rotate in unison therewith and movable laterally and longitudinally thereof, the outer surface of each chaser being provided with serrations extending at an oblique angle to the axis of the body and the inner surface of each chaser having a longitudinal succession of projections and indentures the inner ends of the chaser projections providing internal thrust-faces that bear upon said external thrust-faces during the cutting operation and that pass within the plane of their respective associate external thrust-faces during the collapsing operation, each chaser being adapted to be drawn longitudinally of the body independently of said external thrust-faces through the medium of its oblique serrations during the cutting operation to bring the internal thrust-faces out of line with their respective associate external thrust-faces to permit the chaser to slide inwardly laterally of the body, substantially as described.
2. The combination of a body provided with a longitudinal succession of projections and indentures the outer ends of the body projections providing external thrust-faces, a chaser or chasers connected with the body to rotate in unison therewith and movable laterally and longitudinally thereof, the outer surface of each chaser being provided with serrations extending at an oblique angle to the axis of the body and the inner surface of each chaser having a longitudinal succession of projections and indentures the inner ends of the chaser projections providing internal thrust-faces that bear upon said external thrust-faces during the cutting operation and that pass within the plane of their respective associate external thrust-faces during the collapsing operation, each chaser being adapted to be drawn longitudinally of the body independently of the external thrust-faces through the medium of its oblique serrations during the cutting operation, the outer side of one of the projections of each chaser and the inner side of one of the projections in each of the series of body projections being provided with co-acting stop-faces to arrest the outward movement of each chaser longitudinally of the body, substantially as described.
3. The combination of a body provided with a longitudinal succession of projections and indentures the outer ends of the body projec-

tions providing external thrust-faces, a chaser or chasers connected with the body to rotate in unison therewith and movable laterally and longitudinally thereof, the outer surface of each chaser being provided with serrations extending at an oblique angle to the axis of the body and the inner surface of each chaser having a longitudinal succession of projections and indentures the inner ends of the chaser projections providing internal thrust-faces that bear upon the external thrust-faces during the cutting operation and that pass within the plane of their respective associate external thrust-faces during the collapsing operation, each chaser being adapted to be drawn longitudinally of the body independently of said external thrust-faces through the medium of its oblique serrations during the cutting operation, and a spring adapted to press the chaser or chasers toward and retain said chaser or chasers in alignment with the axis of the body, substantially as described.

4. The combination of a body provided with a longitudinal succession of projections and indentures the outer ends of the body projections providing external thrust-faces, a chaser or chasers connected with the body to rotate in unison therewith and movable laterally and longitudinally thereof, the outer surface of each chaser being provided with serrations extending at an oblique angle to the axis of the body and the inner surface of each chaser having a longitudinal succession of projections and indentures the inner ends of the chaser projections providing internal thrust-faces that bear upon the external thrust-faces during the cutting operation and that pass within the plane of their respective associate external thrust-faces during the collapsing operation, each chaser being adapted to be drawn longitudinally of the body independently of said external thrust-faces through the medium of its oblique serrations during the cutting operation, and a spiral spring having its ends connected together, said spring surrounding the body and chaser or chasers and exerting a yielding pressure against the movement of the chaser or chasers outwardly radially of the body, substantially as described.

5. The combination of a body provided with a longitudinal succession of projections and indentures the outer ends of the body projections providing external thrust-faces, a chaser or chasers connected with the body to rotate in unison therewith and movable laterally and longitudinally thereof, the outer surface of each chaser being provided with serrations extending at an oblique angle to the axis of the body and the inner surface of each chaser having a longitudinal succession of projections and indentures the inner ends of the chaser projections providing internal thrust-faces that bear upon the external thrust-faces during the cutting operation and that pass within

- the plane of their respective associate external thrust-faces during the collapsing operation, and a spring surrounding the body and the chaser or chasers and exerting a yielding 5 pressure against the movement of the chaser or chasers outwardly radially of the body, each chaser being adapted to be drawn longitudinally of the body independently of said external thrust-faces through the medium of its 10 oblique serrations during the cutting operation, and the spring being connected with the chaser or chasers to move in unison therewith longitudinally of the body, substantially as described.
- 15 6. The combination of a body provided with radial slots, chasers located in the slots and movable radially and longitudinally of the body, an abutment rigidly carried by the body and a spring surrounding the body and 20 chasers, one of the edges of said last-named elements being rounded to enable said spring to coact with the abutment to form a yielding catch to regulate the movement of the chasers longitudinally of the body, substantially as 25 described.
7. The combination of a body provided with radial slots, chasers located in the slots and movable radially and longitudinally of the body, an abutment rigidly carried by the body, 30 a spring surrounding the body and chasers, one of the edges of said last-named elements being rounded to enable said spring to coact with the abutment to form a yielding catch to regulate the movement of the chasers longitudinally of the body, and a spring-guard interposed between the spring and the chasers at their intersections and meshing with the chasers to equalize their movements, substantially as described.
- 35 40 8. The combination of a body provided with a longitudinal succession of projections and indentures the outer ends of the body projections providing external thrust-faces, a chaser or chasers connected with the body to rotate in unison therewith and movable laterally and longitudinally thereof, the outer surface of each chaser being provided with serrations extending at an oblique angle to the axis of the body and the inner surface of each chaser having a longitudinal succession of projections and indentures the inner ends of the chaser projections providing internal thrust-faces that bear upon the external thrust-faces during the cutting operation and that pass within 45 the plane of their respective associate external thrust-faces during the collapsing operation, means to adjust the external thrust-faces laterally of the body, and means to retain the external thrust-faces in position when adjusted,
- 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935
9. The combination of a body having a longitudinal succession of projections and indentures the outermost surfaces of the projections providing external thrust-faces which are located upon cam-faces which slope transversely of the axis of the body inwardly from their outermost points to render said external thrust-faces adjustable, a chaser or chasers connected with the body to rotate in unison therewith and movable radially thereof, the inner surface of each chaser being provided with a corresponding succession of projections and indentures the inner ends of the chaser projections providing internal thrust-faces that bear upon the external thrust-faces during the cutting operation and that pass within the plane of their respective associate external thrust-faces during the collapsing operation, one of said parts provided with said succession of projections and indentures being movable longitudinally of the other of said parts so provided, means to adjust the location of said external thrust-faces along said cam-faces relatively to said chasers, and means to hold said cam-faces from rotation independently of body 1 during the collapsing operation, substantially as described.
10. The combination of a body having a longitudinal succession of projections and indentures the outermost surfaces of the projections providing external thrust-faces which are located upon cam-faces which slope transversely of the axis of the body inwardly from their outermost points to render said external thrust-faces adjustable, a chaser or chasers connected with the body to rotate in unison therewith and movable laterally and longitudinally thereof, the outer surface of each chaser being provided with serrations extending at an oblique angle to the axis of the body and the inner surface of each chaser having a longitudinal succession of projections and indentures the inner ends of the chaser projections providing internal thrust-faces that bear upon said external thrust-faces during the cutting operation and that pass within the plane of their respective associate external thrust-faces during the collapsing operation, each chaser being adapted to be drawn longitudinally of the body independently of said external thrust-faces through the medium of its oblique serrations during the cutting operation, means to adjust the location of said external thrust-faces along said cam-faces relatively to said chasers, and means to hold said cam-faces from rotation independently of body 1 during the collapsing operation, substantially as described.
11. The combination of a body having an axial bore, a center piece located in the axial bore and provided with a longitudinal succession of projections and indentures the outer ends of the projections providing external thrust-faces, a chaser or chasers connected with the body to rotate in unison therewith and movable laterally and longitudinally thereof,

the outer surface of each chaser being provided with serrations extending at an oblique angle to the axis of the body and the inner surface of each chaser having a longitudinal succession of projections and indentures the inner ends of the chaser projections providing internal thrust-faces that bear upon said external thrust-faces during the cutting operation and that pass within the plane of their respective associate external thrust-faces during the collapsing operation, one of said parts provided with said succession of projections and indentures being movable longitudinally of the other of said parts similarly provided, and means to hold the center piece from rotation independently of the body in any one of a series of adjusted positions, substantially as described.

12. The combination of a body having an axial bore, a center piece located in the axial bore and provided with a longitudinal succession of projections and indentures the outermost surfaces of the projections providing external thrust-faces which are located upon cam-faces which slope transversely of the axis of the body inwardly from their outermost points to render said external thrust-faces adjustable, and a chaser or chasers connected with the body to rotate in unison therewith and movable radially thereof, the outer surface of each chaser being provided with serrations extending at an oblique angle to the axis of the body and the inner surface of each chaser having a longitudinal succession of projections and indentures the inner ends of the chaser projections providing internal thrust-faces that bear upon said external thrust-faces during the cutting operation and that pass within the plane of their respective associate external thrust-faces during the collapsing operation, one of said parts provided with said succession of projections and indentures being movable longitudinally of the other of said parts similarly provided, means to adjust the location of said external thrust-faces along said cam-faces relatively to said chasers, and means to hold said cam-faces from rotation independently of body during the collapsing operation, substantially as described.

13. The combination of a body having an axial bore, a center piece located in the axial bore and provided with a longitudinal succession of projections and indentures the outermost surfaces of the projections providing external thrust-faces which are cammed transversely of the axis of the body inwardly from their outermost points to render said external thrust-faces adjustable, and a chaser or chasers connected with the body to rotate in unison therewith and movable radially thereof, the outer surface of each chaser being provided with serrations extending at an oblique angle to the axis of the body and the inner surface of each chaser having a longitudinal succession of projections and indentures the inner ends of the chaser projections providing in-

ternal thrust-faces that bear upon the external thrust-faces during the cutting operation and that pass within the plane of their respective associate external thrust-faces during the collapsing operation, one of said parts provided with said succession of projections and indentures being movable longitudinally of the other of said parts similarly provided, and means to hold the center piece from rotation independently of the body in any one of a series of adjusted positions, substantially as described.

14. The combination of a body having an axial bore, a center piece located in the axial bore and provided with a longitudinal succession of projections and indentures the outermost surfaces of the projections providing external thrust-faces which are cammed transversely of the axis of the body inwardly from their outermost points to render said external thrust-faces adjustable, and a chaser or chasers connected with the body to rotate in unison therewith and movable radially thereof, the outer surface of each chaser being provided with serrations extending at an oblique angle to the axis of the body and the inner surface of each chaser having a longitudinal succession of projections and indentures the inner ends of the chaser projections providing internal thrust-faces that bear upon the external thrust-faces during the cutting operation and that pass within the plane of their respective associate external thrust-faces during the collapsing operation, one of said parts provided with said succession of projections and indentures being movable longitudinally of the other of said parts similarly provided, the center piece having a screw-threaded projection, and a nut meshing with said screw-threaded projection and adapted to hold the center piece from rotation independently of the body in any one of a series of adjusted positions relatively thereto, substantially as described.

15. The combination of a body having an axial bore, a center piece located in the axial bore and provided with a longitudinal succession of projections and indentures the outermost surfaces of the projections providing external thrust-faces which are located upon cam-faces which slope transversely of the axis of the body inwardly from their outermost points to render said external thrust-faces adjustable, and a chaser or chasers connected with the body to rotate in unison therewith and movable radially thereof, the outer surface of each chaser being provided with serrations extending at an oblique angle to the axis of the body and the inner surface of each chaser having a longitudinal succession of projections and indentures the inner ends of the chaser projections providing internal thrust-faces that bear upon the external thrust-faces during the cutting operation and that pass within the plane of their respective asso-

ciate external thrust-faces during the collapsing operation, one of said parts provided with said succession of projections and indentures being movable longitudinally of the other of 5 said parts similarly provided, means to adjust the location of said external thrust-faces along said cam-faces relatively to said chasers, and a set-screw carried by the body and adapted

to hold the center piece from rotation independently of the body, substantially as described.
